UNITED STATES PATENT OFFICE.

ERNEST RICHARDSON, OF COLLEGE HILL BOROUGH, PENNSYLVANIA.

ENAMELED RADIATOR AND METHOD OF MAKING THE SAME.

Application filed June 18, 1923. Serial No. 646,125.

To all whom it may concern:

Be it known that I, ERNEST RICHARDSON, a citizen of the United States, residing at College Hill Borough, in the county of Beaver and State of Pennsylvania, have invented new and useful Improvements in Enameled Radiators and Methods of Making the Same, of which the following is a specification.

10 My invention relates to radiators and methods of manufacturing them, and more particularly radiators of the hollow steam and hot-water types.

It is the object of this invention to manufacture enameled cast-metal radiators in such a manner that the enamel will not be overfired or underfired on certain portions. I make all the walls of the radiators of substantially equal thickness so that the enamel thereon will be burned to an equal degree throughout. I have found that, where parts of the cast-metal are substantially thicker than other parts, the enamel on the thinner parts will be overbaked in order to properly bake or burn the thicker portions, and that the thicker parts will be underbaked if the baking is stopped when the thinner parts are properly baked.

Referring to the accompanying drawing, 30 Fig. 1 is a side elevation of a portion of a steam or hot-water radiator; Fig. 2, a central vertical longitudinal section of Fig. 1, before the coat of enamel has been applied thereto, a portion of the metal being broken away; Fig. 3, a view like Fig. 2, but with a coat of enamel thereon; Fig. 4, a horizontal section of Fig. 1 on the line IV—IV; Fig. 5, a horizontal section of Fig. 3, on the line V—V; Fig. 6, an end view of Fig. 1, looking toward the right, a portion being in section; and Fig. 7, a section on the line VII—VII of Fig. 6.

On the drawing, I show three hollow sections 1, 2, and 3 of a steam or hot-water radiator, each section being composed of cast-iron or other metal and being rectangular in shape and having an endless channel 4. The sections are arranged with their sides parallel, their upper and lower portions having the hollow bosses 5. The ends of the hollow bosses on one section abut against the ends of the hollow bosses on the adjacent section with a fluid-tight fit. The channels 4 of the several contiguous sections are in communication with each other by means of the hollow bosses 5.

6 are the legs cast integrally with the end section 1. The radiator so far as described is old and well known. It is to be understood that any suitable number of sections like 2 and 3 may be assembled with the three sections shown and that the final right-hand section will have legs like the section 1. as in well known radiators.

According to the present invention the walls 7 of the sections are cast so as to be of substantially equal thickness throughout. This applies as well to the walls of the bosses 5 as to the walls 7 of the channels 4. The legs 6 which are, in the usual radiator, cast much thicker than the channel walls, are cored out or made hollow, so that the walls 8 of the legs have substantially the same thickness as the walls 7. Even the parts of the wall 7 (Fig. 6) between the legs 6 and the channels 4 are made the same thickness as the channel and leg walls.

Having cast the sections as described, I then coat each section, preferably separately, with enamel except on the ends of the bosses 5, after which I place the sections in a suitable enameling furnace where the enamel is baked or burned on the sections in a manner well known to those acquainted with the art of enameling, the coat of enamel being marked 9 on the drawing. Each section including bosses, and legs, if any, are enameled except as above specified. After the sections have been enameled they are assembled, and clamped together into a rigid unit by means of the usual rods 10. If preferred, the radiators may be assembled before applying the enamel thereto. The enamel referred to herein is preferably of the porcelain type.

By casting every part of each section with an equal wall-thickness, the metal will be evenly heated throughout in the enameling furnace, and, consequently, the enamel will be evenly fired or burned on the sections. Where parts are substantially thicker than other parts, either the thinner parts are overbaked or overburned, or the thicker parts are underbaked or underburned. In either case, a portion of the enamel is damaged.

I claim—

1. The process of manufacturing a hollow enameled cast-metal radiator which consists in forming the radiator with all its walls of substantially equal thickness, coating the exterior walls thereof with enamel, and baking the enamel on the radiator.

2. The process of manufacturing a hollow enameled cast-metal radiator which consists in forming the radiator with hollow metal legs, the walls of the radiator including the 5 walls of the legs being of substantially equal thickness, coating all the said walls externally with enamel, and baking the enamel on the radiator.

3. A radiator comprising a hollow body

supported on hollow legs, the walls of the 10 body and legs being of substantially equal thickness, and a coat of enamel substantially uniformly baked on the outer surface of the said body and legs.

In testimony whereof I hereunto affix my 15 signature this 14th day of June, 1923.

ERNEST RICHARDSON.
